GEAR-SHIFTING MECHANISM

Victor W. Kliesrath and Robert P. Breese, South Bend, Ind., assignors to Bendix Aviation Corporation, South Bend, Ind., a corporation of Delaware

Application August 25, 1933, Serial No. 686,720

28 Claims. (Cl. 192—.01)

This invention relates in general to means for controlling the operation of an automotive vehicle and more particularly to means correlating the control of the internal-combustion engine, the clutch and the change-speed transmission to simplify the technic of operation of these units, minimize the physical effort necessary to their operation and in general provide a simple and effective mechanism for the purposes intended.

10 The trend in the present day automotive vehicle is to power operation of the controls of the power plant; also, to reducing the number and complexity of the controls. It is accordingly the principal object of the invention to provide simply controlled pressure differential operated power means for operating the standard types of clutch and transmission with which the vehicle is equipped, said means to be in part controlled by the means for operating the throttle and the 15 engine and in part by a simple form of manually operated selector.

A further object of the invention is to provide power means for operating the clutch and transmission, which, in a large measure, will be automatic in action and will, with a minimum of operations on the part of the driver, accurately simulate the conventional manual operation of these mechanisms. To this end means are provided for automatically disengaging the clutch 20 by power with a release of the accelerator pedal and therefore after the power of the internal-combustion engine has been reduced to a minimum, said means being so constructed that after the release of the accelerator the transmission 25 may then, but not until then, be operated. The transmission may now be selectively operated for any one of its gear ratios by a single heel and toe operated means, with the exception that in the preferred embodiment of the invention the reverse gear operation of the transmission is effected by said means in conjunction with the operation of a manually operated switch.

The invention also contemplates the provision of interlocking clutch and transmission operating power means, preferably of the manifold vacuum operated type, controlled in part by the accelerator pedal of the vehicle and in part by a left-foot operated selector, the arrangement being such that the transmission may be operated 30 only after the accelerator is released and the clutch disengaged.

With respect to the power operation of the transmission of an automotive vehicle the prior art is replete with suggestions of so-called built-in mechanisms for operating the gear train of

the transmission. Such mechanisms are, however, necessarily complicated and expensive, usually requiring a modification of the standard form of transmission and including numerous conduit, valves, cylinders, etc. The invention is accordingly specifically directed to the power means for operating the transmission, the object being to provide a very simple and economic form of accessory unit adapted to operate the present day type of transmission including a conventional gear-shift lever, the power element of the unit being preferably connected directly to the shift lever to operate the same in a manner fully simulating a conventional operation thereof. To this end there is suggested a pivotally mounted 10 pressure differential operated actuator, operably connected to the shift lever at a point above the floorboard, said actuator being selectively operable to move the shift lever to any one of its conventional positions, and also operable to automatically neutralize the lever and bias the same to a position to shift into either reverse or low gear when the vehicle is static or substantially so.

Yet another object of the invention is to provide a vacuum operated actuator, controlled in 25 part by a manually operated selector valve mechanism, for moving the gear-shift lever to any one of its operative positions, the actuator being bodily movable by a vacuum operated power means, controlled by an automatically operable power 30 operated valve mechanism, said latter valve mechanism cooperating with the aforementioned selector valve mechanism to control the entire sequence of operations of the shift lever. To this end there is provided an actuator comprising 35 two separate vacuum operated motors, the actuator being pivotally mounted for bodily movement in a horizontal plane, said movement being effected by one of said motors mounted on one end of the actuator, both of the motors being controlled in their operation by a valve mechanism 40 also mounted on the end of the cylinder.

A further object of the invention is to provide a composite valve mechanism for controlling the operations of a pressure differential operated actuator, said valve mechanism comprising a manually operated valve mechanism providing two three-way valves and further comprising a power operated three-way valve automatically controlled by a vehicle operated speed-responsive 45 mechanism.

The invention also contemplates the provision of electrically operated means for controlling the neutralizing and laterally movable operations of a gear shift lever operating actuator, said means

comprising a valve member preferably solenoid operated, the solenoid being controlled by a plurality of switches to obtain the aforementioned operation of the motor. To this end there is provided in one suggested embodiment a solenoid operated three-way valve, the solenoid being either energized or deenergized with the mutual operation of one or more of (1) a switch operated by means responsive to the speed of the vehicle; 10 (2) a master switch; (3) the conventional ignition switch of the vehicle; (4) a switch operable by the aforementioned heel and toe operated members; (5) a manually operable switch for cutting out the effect of the last-mentioned 15 switch; and (6) a manually operated emergency switch for rendering the mechanism operative should there be a failure of the aforementioned speed-responsive switch.

A further object of the invention is to provide 20 power means for operating the shift lever to successively select either the second or high gear ratios of the transmission, the low or reverse selection being effected manually. To this end there is provided a double-acting actuator operably connected to the lever and controlled by a two-way operated valve mechanism providing two separate three-way valves to selectively operate the actuator to effect the desired shift. As a further feature of the invention the aforementioned valve mechanism is so designed as to 30 automatically return to a neutral position with release of the valve operating mechanism and thereby deenergize the actuator and leave the shift lever in its operating position.

35 Yet another feature of the above invention lies in the provision of yielding means normally biasing the aforementioned actuator and its connected shift lever to a position to operate the second and high gear shifter rod of the transmission, said yielding means to be overcome in order to effect an operation of the remaining shifter rod.

40 As an alternative embodiment of the aforementioned invention there is suggested the provision of a shift lever operating power means comprising a double-ended actuator operably connected to the shift lever and housing a combined piston and selector valve member, the valve functioning as a power operated relay valve for preselecting the mode of operation of the actuator.

45 Other objects of the invention including the provision of yieldable connection between the power element of the motor and the shift lever to facilitate the operation of the shift lever, the provision of a special mounting for the shift lever motor outside the dash with a manually operable member for operating the lever extending through the instrument board, and including other desirable details of construction and combinations 50 of parts readily suggesting themselves to those skilled in this art will all be apparent from the following description and claims when considered together with the accompanying drawings, in which:

Figure 29 discloses a diagram of a hookup similar to that of Figure 28 with the exception that the master and emergency switches are omitted;

Figure 30 discloses a further modified form of hookup wherein the master, emergency and reverse switches of Figure 28 are omitted; and

Figure 31 discloses a simple form of hookup wherein the neutralizing and biasing operations are effected solely by the manual operation of but one switch.

The present invention in its broadest aspect is directed to power means for operating the standard types of clutch and transmission of an automotive vehicle, said power means being controlled in part by the throttle operating means of the internal-combustion engine. In that embodiment of the invention illustrated diagrammatically in Figures 1 and 2 there is shown a driver's compartment 10, outlined in part by a dash 12 and a toe board 14, and housing a conventional transmission shift lever 16, steering wheel 18, accelerator pedal 20 and clutch and brake pedals 22 and 24. Both the clutch pedal and the shift lever are preferably power operated by manifold vacuum operated double-ended actuators 26 and 28 operatively connected respectively to the clutch pedal 22 and lever 16. The principal elements of the clutch actuator and its control valve mechanism 30 are shown in detail in Figure 16 wherein a double-ended cylinder 32 houses a reciprocable piston element 34 operatively connected to the clutch pedal by a link 36. A conduit 38 interconnects an engine manifold 40, providing a source of vacuum power, with one end of the cylinder 32, the valve mechanism 30, comprising a combined three-way cut-out and bleed valve unit, being incorporated in the connection to control the operation of the clutch motor. A combined three-way and bleed plunger 42 of the valve unit is preferably connected to the accelerator pedal 20. A three-way valve plunger 44, preferably operated from the dash, serves as a cut-out means for rendering the clutch and transmission power means inoperative. The plunger 42 is recessed at 45 to interconnect the manifold and clutch motor to disengage the clutch when the accelerator is released. When the accelerator is operated to speed up the engine the plunger 42 is moved to the left to cut off the connection with the vacuum and vent the motor to atmosphere via a slot 46 in the plunger. The engaging operation of the clutch is thus initiated, the control of the engagement being effected by regulating the rate of efflux of air from the motor via a con-

duit 48 tapped into the casing of the valve unit 30, the air then escaping through a tapered slot 50 in the plunger 42. A slot 52 is provided in the rod 36, permitting a relatively rapid efflux of air from the motor during the first portion of the clutch engaging throw of the clutch pedal, the last stage of the throw being relatively slow by virtue of the relatively slow bleed of air via the slot 50.

The details of the aforementioned clutch operating mechanism form no part of the instant invention, being more fully described and claimed in United States application No. 592,170, filed February 10, 1932, Victor W. Kliesrath, inventor.

The shift lever operating actuator 28, constituting the essence of the present invention, is also connected to the manifold by a conduit 54, said conduit being tapped into the aforementioned conduit 38 at a point between the valve unit 30 and the clutch actuator 26. The three-way valve plunger 42 thus serves as a control valve for both the actuators 26 and 28, the remaining control valve mechanism for the shift lever actuator comprising a combined manual and power operated mechanism 56 housed within one end of the actuator, the same being described in detail hereinafter.

The aforementioned connection of the conduit 54 into the conduit 38 and below the valve unit 30 is an important feature of the invention, inasmuch as the accelerator pedal must be released to operate the three-way valve plunger 42 to interconnect the manifold with the clutch and shift lever motors before the latter may be energized. Thus the clutch is automatically disengaged with release of the accelerator, and furthermore the shift lever may not be operated until the clutch is disengaged.

The accelerator pedal therefore becomes a common control means for (1) idling the engine to create a source of vacuum power and (2) as a means for operating a common control valve for the clutch and transmission operating power means.

Passing now to a more detailed description of the power means for operating the shift lever of the transmission, the actuator 28 is preferably mounted, to swivel in a horizontal plane, by a lug 58 pivoted to a bracket member 60 secured to the dash 12, all as disclosed in Figure 3. The actuator is preferably formed of three body parts 62, 64 and 66, making up two separate vacuum motors. Part 66 is preferably formed as a cylinder stamping, closed at one end by a cap 68 and at its other end by the part 64, and housing a reciprocable piston member 70 connected to the gear shift lever 16 by a connecting rod 72. The piston and cylinder construction provide a pressure differential operated motor 73 for moving the shift lever in conventional fashion in either of two planes of movement for selecting any one of the three forward or reverse gear ratios of the transmission. The actuator body parts 62 and 64 constitute elements of a pressure differential operated vacuum motor 74 operative, in combination with a return spring to be described, to swivel the actuator and its connected shift lever laterally to select one or the other of the aforementioned planes of movement. The parts 62 and 64, preferably formed as castings, are constructed and arranged to house a pressure differential operated diaphragm member 76, the latter being operatively connected, by a link 78, to a lever 80, the latter being pivotally connected at one of its ends to the bracket 60. The 75

lever 80 is adapted to contact a lug 82 extending from the body part 62. Thus with an operative movement of the diaphragm upon energizing the motor 74 the lever 80 is actuated, fulcrumming at 84, to move the actuator bodily in a horizontal plane to the position disclosed in Figure 7. A bias spring 86, interposed between bracket 60 and body member 62, is compressed during this swiveling movement, and upon de-
energizing the motor 74 the spring serves to return the actuator and its connected shift lever to their normal position as disclosed in Figures 3 and 6. This position of the lever insures either a second or high gear operation of the transmission, and the spring 86 thus serves to normally bias the shift lever to this position, the lever being moved by power to its low and reverse gear position.

Both of the aforementioned motors are preferably vacuum operated, as indicated above, and are controlled by the aforementioned valve mechanism 56, which may be housed within the actuator body part 64. The valve mechanism, best shown in Figures 4, 8, 9 and 10, comprises generally a manually operated selector valve member 88 for controlling the actuator to move the shift lever to select the several gear ratios, and a cooperating power operated valve member 90, also controlling the actuator, for automatically neutralizing the shift lever and then moving the same to its low, reverse position when the vehicle is static or substantially so. The valve member 88, which extends laterally through the valve casing, is characterized by two full bodied portions 92 and 94 connected by a spindle portion 96, together forming a recess 98 communicating at all times with a duct 100 interconnected with the conduit 54 leading to the manifold as a source of vacuum. The body member 64 constitutes a major part of the valve structure and is bored to provide ducts 102 and 104 interconnecting a tube 106, extending to one end of the cylinder 66 at a port 107, and ports 108 and 110, the latter adapted to be either covered or uncovered by the valve portion 92 with movement of the valve member 88 to thereby alternately connect a right compartment 112 of the cylinder with the atmosphere or to vacuum. The port 110 interconnects the duct 102 with the atmosphere via a bore 114 in the body of the valve, an air cleaner 116 being provided to filter the air entering the actuator. A port 118 connects a left cylinder compartment 120 with the atmosphere via an opening 122 in the casting, a recess 124 in the valve member 88, openings 126 in a spindle portion 128, and a bore 130 extending throughout the entire length of the valve member and communicating with the air cleaner 116. A port 132 serves to interconnect the latter compartment with the manifold, via recess 98, duct 100 and conduit 54, when the valve member 88 is moved to uncover this port.

The valve member 88 is normally maintained in the position disclosed in Figures 3 and 4, connecting both ends of the cylinder 66 with atmosphere, by means of springs 134 and 136, one or the other of said springs being compressed, to operate the valve and energize the cylinder, by means of a left-foot operated treadle 138.

The treadle is pivotally mounted at its center and is connected by links 140 and 142, bell crank 144 and link 146 to the valve member 88. Thus a heel or toe operation of the treadle will operate the valve member in one direction or the other to energize the actuator to actuate the shift

lever. These operations and the position of the parts assumed will be described in greater detail hereinafter in reviewing the operation of the mechanism.

The power operated valve member 90, shown in detail in Figure 4, comprises a piston member extending vertically through a valve casing 147. The piston member is recessed at 148, a full bodied end portion 150 being adapted, with movement of the valve to the right, to uncover a port 152 intercommunicating the manifold, via the duct 100 and recess 98, with a duct 154, a recess 156, a duct 158 and a tube 160, the latter extending parallel to the cylinder 66 and secured thereto. Further movement to the right of the valve member 90 serves to uncover a port 162, shown in dotted lines in Figure 3, to intercommunicate the manifold with a right compartment 164 of the vacuum motor 74. A duct 166 interconnects the air cleaner 116 with the recess 148 in the valve member 90 to connect the atmosphere with the compartment 164 when the valve member 90 is in its extreme left position. At this time the port 152, leading to the tube 160, is covered.

The valve member 90 is moved to the right, to uncover the ports 152 and 162 and cover the duct 166, by a solenoid 168 comprising a winding 170 and an armature 172, the latter constituting an end extension of the body of the valve member. The solenoid is energized, to operate the valve, with the closing of (1) a standard ignition switch 174 of the vehicle, (2) a master switch 176, and (3) a speedometer operated switch 178, all switches being in series with a winding 180 of a relay 182. A wiring diagram is disclosed in Figure 11. The relay is closed, with the closing of the aforementioned switches, to thus energize a circuit, including the solenoid 168, and effect the aforementioned operation of the valve 90.

An important feature of the invention relates to the speedometer or equivalent speed-responsive operated switch 178, the same being constructed and arranged to close when the vehicle is static or substantially so. There is schematically disclosed in Figures 12 and 13 one form of speedometer operated switch comprising a conventional speedometer casing 184 grounded at 186 and housing a shaft 188 driven by the propeller shaft of the vehicle. A spring returned disk 190 and an indicating needle 192 are mounted on the shaft 188 to rotate therewith, the disk being provided with a contact lug 194 adapted, when the speedometer registers zero or substantially zero, to contact a buffer spring 196, the latter being pressed into contact with a contact spring 198 wired to the winding 180 of the relay. The springs 196 and 198 are preferably mounted on the shell 184 and are insulated therefrom at 200.

The complete technic of operation of the aforementioned mechanisms will now be described in detail. Assuming the vehicle at a standstill and the engine dead, the ignition switch 174 is first turned on and the engine cranked: the pumping pistons of the idling engine then develop a manifold vacuum of approximately twenty inches of mercury at sea level, thus creating an ample source of power to operate both the clutch and transmission operating motors.

The accelerator being released, the three-way valve plunger 42 connects the manifold with the clutch motor to automatically disengage the clutch: the connection between the manifold and control valve mechanism 56 of the shift lever 75

actuator is also opened to permit an operation of the transmission operating lever 16 to shift into any one of low, reverse or second gears as is desired. It is also to be noted that at this time there is a direct connection between the manifold and the vacuum motor 74, inasmuch as the solenoid 168 is energized to move the valve member 90 to the right and uncover ports 152 and 162, the connection being made via conduits 38 and 54, duct 100 and recess 98. The motor 74 is thus energized by evacuating the compartment 164 thereof, the atmosphere, acting upon the diaphragm 76, entering the compartment via an opening 202 in the member 62. The lever 80 connected to the diaphragm is thus urged outwardly to bodily move the actuator and its connected shift lever against the action of spring 86 and position the actuator, as shown in Figure 7, preparatory to effecting either a low or reverse shift of the transmission.

If it is then desired to place the transmission in low gear, the operator depresses the heel portion of the treadle 138 to move the valve member 88 to the position shown in Figure 8 to interconnect the manifold with the right compartment 112 of the motor 73 via duct 100, recess 98, port 108, ducts 102 and 104 and tube 106: atmosphere is, at this time, admitted to the left compartment 120 of the motor via the air cleaner 116, bore 130, openings 126, port 132 and duct 122. The piston is thus forced to the right to the full line position of Figure 7, moving the shift lever 16 to its low gear position. With release of the treadle 138 the spring 134 returns the valve member 88 to its neutral position, shown in Figure 4, to vent both compartments of the motor to atmosphere: the shift lever remains in position however and the accelerator is now depressed to engage the clutch to get the vehicle under way.

When the desired speed of the vehicle has been reached in low gear, the operator depresses the toe portion of the treadle to select the second gear position of the shift lever. The valve member 88 is by this operation drawn outwardly to the position of Figure 9, the left compartment 120 of the motor 73 being connected to the manifold via duct 100, recess 98, port 132 and duct 122: the right compartment 112 of the motor is at this time connected to the atmosphere via air cleaner 116, bore 114, ports 108 and 110, ducts 102 and 104 and tube 106. Thus the piston 70 of the motor is forced to the left under the pressure of the atmosphere to the position shown in full lines in Figure 6, and the shift lever is moved to its second gear position. Release of the treadle 138 will again permit the valve 88 to be neutralized by its spring 136, the shift lever remaining in position.

It will be noted that the shift lever in moving from the low to the second gear position was forced to move laterally through the gate in the transmission, this movement being effected by the angular bodily movement of the actuator under the action of the spring 86. This action of the spring was insured by virtue of the deenergizing of the vacuum motor 74 when the vehicle was placed in motion, the speedometer operated switch 178 being opened when the lug 194 moved away from the spring 196 to thereby deenergize the solenoid 168 and permit a return of the valve member 90 under the action of a return spring 204. This position of the valve member 90 is shown in Figure 9, the compartment 164 of the motor 74 being connected to atmosphere via air cleaner 116, duct 166, recess 148 and port 162.

In Figure 8 the valve member 90 is shown in its operative position to energize the motor 74. The actuator is thus biased by vacuum power to its low and reverse gear position when the vehicle is static and is biased to the second and high gear position when the vehicle is in motion.

The desired speed of the vehicle having been reached in second gear, the treadle is now again heel operated to move the valve 88 to the position of Figure 10, similar to the position of Figure 8, whereupon the motor 73 is again energized to move the shift lever to its high or third gear position. When driving in high gear the operator may step the gear ratio down to second gear with a toe operation of the treadle, as is obvious from the aforementioned description.

When the vehicle is brought to a stop, the shift lever is automatically neutralized, irrespective of the then existing position of the lever, the piston 70 moving to the position of Figure 3. This operation is effected by virtue of the aforementioned operation of the solenoid when the vehicle is static, the valve member 90 being automatically operated to uncover the port 152 to vacuum. The manifold is then connected, via duct 154, recess 156 and duct 158, with an opening 206, shown in Figures 3 and 5, in the tube 160. The connection between the tube 160 and the interior of the cylinder is made by a cup member 208 fixed to the cylinder 66 over an opening 210 therein, the tube 30 extending through the cup.

Thus one or the other of the compartments of the motor 73 is automatically connected to the manifold when the vehicle is stopped to draw the piston 70 to the center of the cylinder until the hole 210 in the cylinder is covered: piston sealing rings 212 are preferably made of a width to equal the width of the opening 210. The shift lever is thus automatically moved to its neutral position in the gate of the transmission when the vehicle is stopped, and it should be remembered, as has been previously described, that the lever is also automatically moved through the gate in the transmission over to the low and reverse gear position of the lever. The shift lever is then in position to repeat the above described cycle of operations.

Should the operator desire to shift into second gear from a standing start, the treadle is toe operated, resulting in an operation of the mechanism not heretofore described but which constitutes an important feature of the invention; for it will be noted that some means must be provided, operative to automatically cut out the operation of the motor 74, biasing the actuator and its lever to the left, and to insure an operation of the spring 86 to move the same to the right, prior to the forward movement of the piston 70 resulting from an operation of a valve member 88. Otherwise, the motor 74 would remain operative, moving the shift lever to place the transmission in reverse. To this end there is provided a switch 214 in series with the winding of the solenoid 168 and comprising a plunger 216, biased by a spring 218 to bridge contacts 220 by a contact 222, the end of the plunger abutting a fillet 224, at the junction of a two-diamented portion 226 of a stem 228 of the valve member 88, when the member is in its neutral or off position, all as disclosed in Figures 3 and 11.

A very slight movement of the valve member 88 will thus result in moving the switch plunger 216 sufficiently to separate the contacts to deenergize the solenoid, resulting in a closing of the valve member 90 by its return spring 204 and a

venting of the motor 74 to then permit the spring 86 to move the shift lever through the gate of the transmission. The parts are so constructed and arranged as to insure this result prior to any movement of the piston 70 resulting from an operation of the valve member 88 to the position disclosed in Figure 9. The shift lever is thus moved to its second gear position with a toe operation of the treadle despite the fact that the vehicle is stationary.

Obviously, the aforementioned mechanism will prevent the transmission's being placed in reverse; therefore as a further feature of the invention there is provided a manually operated switch 230, preferably conveniently mounted on the instrument board or on the steering wheel, closing what may be termed a jumper circuit to operate the solenoid. Thus the effect of opening the valve operated switch 214 is destroyed when the operator manually closes the switch 230, and the shift lever is maintained in position by the motor 74 to permit the shift lever to be moved by the motor 73 to its reverse gear position. The operation of the switch 230 and the circuit that it controls is disclosed in the wiring diagram of Figure 11.

If desired, a manually operable switch 232 may also be conveniently located, preferably in the dash and adjacent the switch 230, said switch functioning to shunt the master switch 176 and speedometer controlled switch 178; thus should either or both of the latter switches fail, the solenoid would nevertheless be rendered operable for the purposes intended. The function of the master switch 176 is to render the motor 74 inoperative, whereupon it becomes necessary to manually neutralize the shift lever and move the same through the gate of the transmission. It will also be noted that an excessive drain of the battery is obviated by placing the ignition switch 174 in series with the relay.

There is thus provided a substantially fool-proof mechanism for operating a conventional gear-shift lever by power, the mechanism in its operation fully simulating a conventional manual operation of the lever.

Alternative embodiments of the invention are disclosed diagrammatically in Figures 14, 15, 17, 22 and 25. Figures 14 and 15 disclose different types of speed-responsive mechanism for operating the valve member 90, the modification of Figure 14 providing a spring 234 to move a lever 236 to open the valve when the vehicle is static or substantially so, the spring being overcome, to close the valve, by a vehicle propelled shaft driven flyball governor 238 when the vehicle is in motion. In Figure 15 there is disclosed a spring 240, housed within a fluid motor 242, operative to move a piston 244 and its connected valve member 90 to open the valve when the vehicle is static, the spring being compressed to close the valve, by fluid pressure derived from a vehicle propeller shaft driven fluid pump 246, when the vehicle is in motion.

There is disclosed in Figures 17-20, inclusive, a mechanism similar in operation to the mechanism of Figure 1 with the exception that the power means for neutralizing the shaft lever and biasing the same to its low and reverse position is omitted. A double-acting actuator 300 is pivotally mounted to the dash at 302, its reciprocable piston 304 being substantially universally connected to a shift lever 306 by a yieldable bracket connection 308; this connection, which is disclosed in detail in Figure 21, preferably comprises a relatively

soft rubber portion 310, internally tapered to snugly fit over the shift lever, and a relatively hard rubber portion 312 vulcanized to the portion 310 and provided with internal threads 314 therein adapted to receive a threaded end 316 of a connecting rod 318. The yieldable connection 308 is not claimed herein inasmuch as the same constitutes the invention of Willard Paine, the same being disclosed and claimed in an application No. 690,641, filed September 23, 1933. A spring 320 serves to bias the actuator to the right to insure a power operation of the shift lever. The valve mechanism for controlling the operation of the actuator is preferably built into an end member 322 of the actuator constituting a valve part and comprises a reciprocable piston member 324 operatively connected to a two-way operated treadle 326 by linkage 328. The piston is recessed at 330, opposite a vacuum port 332 in the member 322, said piston being provided with openings 334 interconnecting a longitudinally extending bore 336 in the piston with a piston receiving bore 338 in the member 322, the bore being capped at its end by an air cleaner 340. The valve member 322 is provided with ducts 342 and 344 connected respectively with a forward compartment 346 of the actuator and with a tube 348 the latter extending exteriorly of the actuator and lengthwise thereof to be tapped into the rear end of the actuator to interconnect a rear compartment 350 thereof with the valve mechanism. Valve springs 352 serve to return the piston to a neutral position to vent both ends of the actuator to atmosphere and close off the vacuum connection when the treadle is released.

In operation, either a heel or toe actuation of the treadle 326 serves to connect one or the other of the compartments 346 and 350 of the actuator with the manifold via ducts 342 or 344, recess 330, port 332 and a conduit 354 to energize the actuator to effect either a second or high gear shift of the transmission. It will be noted that the conduit 354 is connected directly with the manifold in the embodiment of Figure 17 thus eliminating the vacuum interlock feature previously shown and described.

There is sectionally disclosed in the lower part of Figure 17 a form of combined centrifugal and vacuum operated clutch structure with which the transmission operating power mechanism is adapted to cooperate. A connecting rod 356 of a clutch motor 358 is connected to a crank arm 360 adapted, when the motor is energized, to disengage the clutch, to actuate a crank member 362 to force a sleeve member 364 to the left to operate a plurality of lever members 366. The lever members are fulcrumed on cross pins 368 secured to pins 370, the latter being fixed to a housing member 372 secured to the flywheel rotor member 374 of the clutch. Lever members 366 are adapted, when actuated, to force pins 376 and a connected flange 378 of a pressure plate 380 laterally to the right to move a ring member 382 out of contact with a friction disk 384, the latter being slidably keyed to a vehicle drive shaft 386. The plate 380 and ring 382 thus form relatively movable parts of a laterally movable clutch engaging unit. Spring pressed pins 388 serve to secure the ring 382 to the pressure plate 380 and also serve to maintain a plurality of spaced centrifugal weight members 390 in position, a shank portion 392 of each weight member extending through an opening 394 in plate 380 and into a recess 396 in the face of the ring. A plurality of clutch springs 398, interposed between the

housing member 372 and the pressure plate 380, normally tend to keep the clutch engaged by maintaining the friction disk 384 pressed into contact with the flywheel 374 by the pressure plate unit.

With release of an accelerator pedal 400 the clutch operating motor 358 is energized to move the crank 360 to actuate the levers 366 and compress the clutch springs 398 to disengage the clutch. In this operation the pressure plate and ring unit is preferably moved far enough away from the friction disk 384 to completely disengage the unit from the disk, irrespective of the position of the ring 382 with respect to the plate 380 under the action of the weights 390. With an operation of the accelerator to step up the speed of the engine the clutch motor is de-energized, permitting the clutch springs 398 to move the plate and ring unit to the left to force the friction disk 384 into engagement with the flywheel 374 and engage the clutch. The pressure of the clutch springs is augmented by the action of the weights 390, which are moved outwardly by centrifugal force, the shank portions thereof acting as levers to separate the ring 382 from the plate 380. The force exerted by the weights is a function of the engine speed, inasmuch as the centrifugal force energizing the weights is directly proportional to said engine speed. The clutch is thus engaged in accordance with the mode of operation of the accelerator, which simulates a conventional manual operation of the clutch. The bleed control of the clutch motor 358, as described hereinafter, is also regulated to so control the clutch engaging action of the clutch springs as to cooperate with the centrifugal weights and insure their clutch engaging action as just described. Preferably in starting the vehicle the entire loading of the clutch is effected by the centrifugal weights, the bleed control of the clutch motor being such as to delay the loading from the clutch springs until the vehicle is under way; this is usually effected in from four to six seconds. Should the clutch 45 slip as in laboring on a hill the clutch springs will at the end of the aforementioned period become effective to augment the action of the weights and insure an adequate loading of the clutch to properly accelerate the vehicle.

The clutch operating mechanism of Figure 17 preferably comprises the aforementioned actuator 358 connected to a manifold 401 by a conduit 402 at a point just above a throttle 404 the latter functioning as a three way valve similar to the valve 42 of Figure 16. A spring operated check valve 406 in the vacuum connection, described in detail in Figure 17a, permits the disengagement of the clutch a valve 406' automatically inserting to interconnect the manifold and actuator when the throttle is closed. A small opening 406" in the valve member 406' provides a fixed bleed of air back into the actuator to control the rate of clutch engagement when the throttle 404 is opened.

There is disclosed in Figures 22, 23 and 24 an embodiment of the invention wherein the actuator for operating the shift lever houses a power operated valve mechanism functioning to pre-select the mode of operation of the actuator. Similar to the previously described modification of Figure 17 a double-ended actuator 407 is pivotally secured to the dash at 408 and a reciprocable piston 410 therein is universally connected to a shift lever 412 by a connecting rod 414 the latter having a ball and socket connection 416

with an arm 418 secured to the lever. A hub portion 420 of the piston 410 is slidably mounted on an enlarged end member 422 of the connecting rod 414, the two parts being provided with cooperating ducts to provide a valve member. A conduit 424 interconnects a vacuum port 426 in the rod 414 with a manually operated control valve 428, the latter being connected with the previously described clutch control mechanism of Figure 16.

Depression of a treadle 430 moves a spool-shaped piston member 432 of the valve 428 to first cut off the connection of the conduit 424 with the atmosphere at a port 434 and then interconnect said port and a port 436 through the spool valve member 432 to interconnect the actuator with the source of vacuum. The actuator is thus energized, to move the shift lever to its high gear position, by the evacuation of the air from a rear compartment 438 of the actuator via a duct 440 in the hub 420, cross ducts 442 in the member 422, a tube 444 in the connecting rod and conduit 414, the atmosphere entering a forward compartment 446 of the actuator via cross and longitudinally extending ducts 448 and 450 in the member 422, and a tube 452 constituting a portion of the connecting rod. The above described operative position of the parts is disclosed in full lines in Figure 23, wherein the piston member 410 and rod 414 have been moved to their extreme right position.

With release of the treadle 430 by a return spring 454 the spool valve 432 is again returned to a position to cut off the vacuum connection with the actuator and interconnect the same with the atmosphere. Air then enters the right compartment 438 of the actuator to equalize the absolute pressure in each compartment of the actuator whereupon the piston 410 is moved to the left by a spring 456 to a position disclosed in Figure 26. The spring 456 is compressed with the power stroke of the piston to the position of Figure 23, and with the equalization of absolute pressures on either side of the piston the spring automatically functions to slide the piston over the member 422 as just described. The parts are now in position to effect a reverse power stroke of the piston to move the shift lever to its second gear position, and it will be noted that the relatively movable piston hub 420 and connecting rod end member 422 provide in effect a power operated relay valve, the valve 428 functioning as a manually controlled master valve.

The master valve 428 is then again manually operated as before to evacuate the forward compartment 446 of the actuator via one of the ports 440, cross ports 442, tube 444 and conduit 424, atmosphere entering the rear compartment 438 via an atmospheric port 458, the tube 452 and ports 460 in the member 422. The piston is thus power operated to the left from the position of Figure 24 to move the shift lever into its second gear position, and when the treadle is released, after the completion of the power stroke, the piston hub 420 is automatically moved over the member 422 to the right to the dotted line position of Figure 23 by a spring 462 operating the valve to pre-select the subsequent operation of the actuator: the parts will then be in position to effect another power stroke to move the shift lever to its high gear position.

There is thus provided means for alternately power operating the shift lever from high to second and back again without conscious effort on the part of the driver to select an operation

of the valve, for all that is necessary is to depress the treadle 430. As with the previously described embodiments of Figure 17, a spring 464 serves to bias the actuator to the second and high gear positions of the shift lever.

The actuator may be neutralized manually by the shift lever, inasmuch as the piston 410 is normally atmospheric suspended.

There is disclosed in Figures 25 and 26 an alternative embodiment of the invention wherein a pressure differential operated actuator 463 is mounted, by brackets 465 and 466, to the outside of a dash 468, a piston 470 thereof being operably connected to a shift lever 472 by a connecting rod 474, bell crank 476 and link 478. The shift lever is preferably so curved as to extend beneath an instrument board 480 to thus increase the leg room of the driver.

The actuator 463 is identical with that disclosed in the modification of Figure 1 with the exception that the diaphragm motor at the end of the actuator is omitted the same being replaced by a solenoid 482 shown in Figure 26 and described hereinafter. A valve mechanism 484, similar in every detail to that disclosed in Figure 4, serves to control the operation of the actuator the valve being operated by a treadle 486 interconnected therewith by links 488 and 490 and a bell crank 492. Inasmuch as the biasing vacuum operated power means has been omitted from the actuator of this embodiment some means must be provided for taking its place and to this end there is suggested a combined solenoid and spring mechanism disclosed in Figure 26. The lever 472 is provided at its end with a socketed fitting 494 to receive a ball 496 on the end of the lever. A laterally extending biasing spring 498 interconnects one side of the fitting with a side wall 500 of the driver's compartment or other rigid portion of the vacuum body and a laterally extending cable 502 interconnects the other side of the fitting with the armature of the solenoid 482 the latter also being secured to a rigid portion 504 of the vehicle. The solenoid 482 is preferably connected in parallel with the solenoid of the valve mechanism 484 as disclosed in the wiring diagram of Figure 27; otherwise the electrical hookup is identical with that disclosed in Figure 11.

The operation of the aforementioned mechanism will be apparent, the same being identical in function with that of the mechanism disclosed in Figure 1; with an idling engine, the master switch 176 closed and the vehicle static. The speedometer controlled switch 178 is closed to close the relay 182 and energize the solenoids 168 and 482. The shift lever is thus first neutralized by the actuator 463 and then moved, against the tension of the spring 498, to its low and reverse gear position. The actuator may now be energized, by the operation of its treadle operated selector valve mechanism, to move the shift lever to any one of its reverse, low or second gear positions, the reverse gear position being made possible by the temporary manual closing of the reverse switch 430 all as previously described; in short, the shift lever may be operated in the same manner as that of the mechanism of Figure 1, solenoid 482 and the spring 498 functioning in a manner similar to the motor 74 and spring 76 of the previously described mechanism.

An important feature of the mechanism of Figure 25 is in the provision of a manually operable connection comprising a link 506 and a handle 508 pivotally connected to the fitting 494 of

the shift lever by ears 510 and extending through the instrument board 480. Thus at the option of the driver the shift lever may be manually operated in conventional fashion, a push and pull action selecting the gear ratios and neutralizing the lever and an oscillatory action moving the lever through the transmission gate to either of its low and reverse or second and high positions.

There are disclosed in Figures 28 to 31 inclusive, alternative electrical hookups for controlling the operation of the solenoid operated valve 90, the latter controlling the neutralizing and biasing operations of the actuator.

The hookup of Figure 28 is similar in operation to that of Figure 11, previously described, with the exception that the master switch 176 simultaneously opens or closes both the relay and solenoid circuits and the emergency switch 232 is placed in the solenoid circuit, shunting the relay 132. Thus with an opening of the master switch 176 the entire electrical hookup of Figure 28 is rendered inoperative, whereas with the embodiment of Figure 11 the solenoid 168 might have been energized with an operation of the reverse switch 230; furthermore, by placing the emergency switch in the solenoid circuit and shunting the relay there is provided a means for rendering the mechanism operative despite a failure of either the speedometer switch or relay; otherwise the hookups of Figures 11 and 28 are identical in operation.

The systems disclosed in Figures 29, 30 and 31 are designed to simplify the system of Figure 28 by eliminating certain of the control switches, that of Figure 29 eliminating the master and emergency switches, that of Figure 30 further simplifying by eliminating the master, emergency and reverse switches, and the system of Figure 31 providing by a single manually operated switch 512 for controlling the solenoid 168.

It will be understood that while a plurality of embodiments of the invention are described as shown, a considerable latitude is to be permitted in construction within the scope of the appended claims.

We claim:

1. Power means for operating the gear shift lever of a three-speed forward and reverse transmission of an automotive vehicle comprising a laterally movable and double-acting pressure differential operated actuator operable to simulate a conventional operation of the gear shift lever, and valvular means for controlling the operation of said actuator, said means being both manually and power operated and operative to provide a coordinated selective and automatic control of said actuator.

2. Power operated accessory means for operating the shift lever of a three-speed forward and reverse transmission of an automotive vehicle comprising a pressure differential operated actuator having its power element operatively connected to said lever to move the same in either one of two planes of movement said actuator further comprising power means for bodily moving said actuator and its connected lever in a third plane of movement to select one or the other of the aforementioned planes of movement, and valvular mechanism for controlling the aforementioned operations of said actuator.

3. Power operated accessory means for operating the shift lever of the transmission of an automotive vehicle comprising a pressure differential operated actuator having its power element operatively connected to said lever to move the lever in

either one of two planes of movement, said actuator comprising power means for bodily moving itself and its connected lever in a third plane of movement to so position the actuator as to permit the operation of the lever in either one or the other of the aforementioned planes of movement, and valvular mechanism for controlling the aforementioned operations of said actuator.

4. Power operated accessory means for operating the shift lever of the transmission of an automotive vehicle comprising a pressure differential operated actuator having its power element operatively connected to said lever to move the lever in either one of two planes of movement, said actuator comprising power means for bodily moving itself and its connected lever in a third plane of movement to so position the actuator as to permit the operation of the lever in either one or the other of the aforementioned planes of movement, and a manually and power operated valvular mechanism for controlling the aforementioned operations of said actuator.

5. Power operated accessory means for operating the shift lever of the transmission of an automotive vehicle comprising a pressure differential operated actuator having its power element operatively connected to said lever to move the same in either one of two planes of movement, said actuator comprising power means for bodily moving said actuator and its connected lever in a third plane of movement to so position the actuator as to permit the operation of the lever in either one or the other of the aforementioned planes of movement, and a manually and power operated valvular mechanism for controlling the aforementioned operations of said actuator, the manual operation of the valvular mechanism energizing the actuator for effecting the first mentioned operations of the shift lever and the power operation of the valve mechanism energizing the actuator to effect the last-mentioned operation of the shift lever.

6. Power means for operating the gear shift lever of an automotive vehicle comprising an actuator operatively connected to said lever, valve mechanism for controlling the operation of said actuator to energize the same to move said lever in such fashion as to fully simulate a conventional manual operation thereof, and automatically operable means for operating said valve mechanism to effect a movement of said lever to a position to select either a low or a reverse gear operation of the transmission, said means being only operative when the vehicle is static or substantially so.

55. 7. Power means for operating the gear shift lever of an automotive vehicle comprising an actuator operatively connected to said lever, valve mechanism for controlling the operation of said actuator to selectively operate the same to move said lever in such fashion as to fully simulate a conventional manual operation thereof, and automatically operable means for operating said valve mechanism energizing said actuator so as to bias said lever to a position to effect either a low or a reverse gear operation of the transmission, said valve operating means being operative when the vehicle is static or substantially so.

8. Means for operating the gear shift lever of an automotive vehicle comprising a unitary power means operatively connected to said lever, valve mechanism for controlling the operation of said unitary power means, automatically and selectively operating the same to move said lever in such fashion as to fully simulate a conventional manual operation thereof, the selective operation

of said valve mechanism effecting any one of the selections of the transmission, and vehicle operated speed-responsive means for operating said valve mechanism energizing said actuator so as to bias said lever to a position to effect either a low or a reverse gear operation of the transmission, said valve operating means being operative when the vehicle is static or substantially so.

9. Power means for operating the gear shift lever of an automotive vehicle comprising an actuator operatively connected to said lever, valve mechanism for controlling the operation of said actuator automatically and selectively operating the same to move said lever in such fashion as to fully simulate a conventional manual operation thereof, and a speedometer operated switch for controlling the operation of said valve mechanism energizing said actuator so as to bias said lever to a position to effect either a low or a reverse gear operation of the transmission, said valve operating means being operative when the vehicle is static or substantially so, and other means for operating said valve mechanism to energize said actuator to select any one of the three forward or reverse gear selections of the transmission.

10. In an automotive vehicle provided with an internal-combustion engine, a clutch and a gear shift lever, manifold vacuum operated power means for operating the clutch and transmission, valvular means for controlling the operation of the power means to successively disengage the clutch and effect a combined selective and automatic operation of the shift lever, and means for operating said valvular means comprising means operative in accordance with the speed of the vehicle, the selection of the valvular means being effective to so control the operation of the power means as to establish one of a plurality of the settings of the transmission.

11. In an automotive vehicle provided with an internal-combustion engine, throttle operating means, a clutch and a gear shift lever, manifold vacuum operated power means for operating the clutch and transmission, valvular means for controlling the operation of the power means to successively disengage the clutch and effect a combined selective and automatic operation of the shift lever, said valvular means comprising a plurality of valves including a three-way valve operated by said throttle operating means, and further comprising a heel and toe operable valve for in part controlling the power operation of the shaft lever together with means for operating one of said valves including a control element operable when the speed of the vehicle is reduced to a predetermined value.

12. In an automotive vehicle provided with a three-speed forward and reverse transmission mechanism, power means for operating the transmission to simulate a conventional manual operation thereof, said power means comprising an actuator operably connected to the transmission and a valve mechanism for controlling the actuator, said mechanism comprising selectively operable means for energizing the actuator to place the transmission in any one of its operative positions and further comprising automatically operable means, operative when the vehicle is static, or substantially so, to first neutralize the transmission and then bias the same to insure the selection of any one of its low or reverse speed settings.

13. In an automotive vehicle provided with a three-speed forward and reverse transmission, power means for operating the transmission to

- simulate a conventional manual operation thereof, said power means comprising an actuator operably connected to the transmission and a valve mechanism for controlling the actuator,
 5 said mechanism comprising manually operated selectively operable means for energizing the actuator to place the transmission in any one of its operative positions and further comprising vehicular operated speed responsive means for first
 10 neutralizing the transmission and then operating the same to insure the selection of any one of its low, reverse, or second speed settings.

14. In an automotive vehicle provided with a three-speed forward and reverse transmission
 15 mechanism, power means for operating the transmission to simulate a conventional manual operation thereof, said power means comprising an actuator operably connected to the transmission and a valve mechanism for controlling the actuator,
 20 said mechanism comprising a heel and toe operated means for energizing the actuator to place the transmission in any one of its operative positions and further comprising speedometer controlled means for first neutralizing the transmission
 25 and then rendering the same operative to insure a subsequent selection of any one of its low, reverse or second speed settings.

15. Power means for operating the shift lever of a three-speed forward and reverse transmission
 30 of an automotive vehicle comprising a single actuator operably connected to the lever and pivotally mounted to move bodily in a horizontal plane, power means for biasing said actuator and its connected lever to a position to effect either a low or a reverse shift of the transmission, and means for controlling the operation of the actuator to effect the desired shift of the transmission.

16. Power means for operating the shift lever of a three-speed forward and reverse transmission
 40 of an automotive vehicle comprising a single actuator operably connected to the lever and pivotally mounted to move bodily in a horizontal plane, automatically operated power means for biasing said actuator and its connected lever to a position to effect either a low or a reverse shift of the transmission at zero or substantially zero
 45 vehicular speed, and means for controlling the operation of the actuator to effect the desired shift of the transmission.

50 17. Power means for operating the shift lever of the transmission of an automotive vehicle comprising a single double-acting actuator operably connected to the lever and pivotally mounted to move bodily in a horizontal plane, automatically operated power means for biasing said actuator and its connected lever to a position to effect either a low or a reverse shift of the transmission at zero or substantially zero vehicular speed, and manually operated means for controlling the
 55 operation of the actuator to effect the desired shift of the transmission.

18. Power means for operating the shift lever of an automotive vehicle to simulate a conventional manual operation thereof comprising a
 60 power actuator operably connected to said lever within the driver's compartment, said actuator comprising power means operable when the vehicle is static or substantially so, to automatically move said actuator bodily to move the lever to its position to effect either a low or a reverse gear operation of the transmission, means for automatically returning said actuator and its connected shift lever to a position to effect either a second or a high gear shift of the transmission when the vehicle is in motion, and means for con-

trolling the energization of said actuator to move the shift lever to effect any one of the three forward or reverse gear selections of the transmission.

19. A manifold vacuum operated power means for operating the shift lever of an automotive vehicle to simulate a conventional manual operation thereof comprising a power actuator operably connected to said lever within the driver's compartment, said actuator comprising power means operable when the vehicle is static or substantially so, to automatically move said actuator bodily to move the lever to its position to effect either a low or a reverse gear operation of the transmission, a spring operated lever means for automatically returning said actuator and its connected shift lever to a position to effect either a second or a high gear shift of the transmission when the vehicle is in motion, and means for controlling the energization of said actuator to move the shift lever and effect any one of the three forward or reverse gear selections of the transmission.

20. Power means for operating a three-speed forward and reverse transmission of an automotive vehicle comprising a power actuator operably connected to the shifter rods of said transmission, said actuator comprising power means, automatically operable when the vehicle drive shaft is static or substantially so, to operate said actuator to insure a low or reverse selection of the transmission, and means for controlling the operation of the actuator to select any one of the low or reverse gear ratios of the transmission when the aforementioned automatically operated power means is in operation.

21. Power means for operating a variable forward speed and reverse transmission of an automotive vehicle comprising a power actuator operably connected to the transmission, said actuator comprising power means for bodily moving said actuator to insure either a low or a reverse gear operation of the transmission when the vehicle is static or substantially so, said actuator comprising other power means for bodily moving said actuator to insure either a second or a high gear operation of the transmission when the vehicle is in motion, valve means for controlling an operation of the actuator to effect any one of the gear ratio settings of the transmission, and other valve means, cooperating with said last-mentioned valve means, for controlling the aforementioned power means to effect the aforementioned bodily movements of the actuator and also serving to control the same to automatically neutralize the transmission when the vehicle is static or substantially so.

22. Power means for operating the variable forward speed and reverse transmission of an automotive vehicle comprising a double-acting power actuator operably connected to the transmission, said actuator comprising power means for bodily moving the same to insure either a low or a reverse gear operation of the transmission when the vehicle is static or substantially so, spring operated lever means for bodily moving said actuator to insure either a high or a second gear operation of the transmission when the vehicle is in motion, a manual two-way operated valve means for controlling the operation of the actuator to effect any one of the gear ratio settings of the transmission, and a power operated valve means, cooperating with said last-mentioned valve means, for controlling the aforementioned power means to effect the bodily

movement of the actuator and also serving to control the same to automatically neutralize the transmission when the vehicle is static or substantially so.

5 23. In an automotive vehicle provided with a variable forward speed and reverse transmission, power means for operating the transmission comprising a power actuator operably connected to the transmission, means for controlling the operation of said actuator to insure either (1) a low or reverse operation of the transmission or (2) a second or high gear operation of the transmission by the actuator, the operation of said means being a function of the condition of the vehicle, that is whether static or kinetic, and means for controlling the operation of the actuator to select any one of the gear ratios of the transmission.

10 24. In an automotive vehicle provided with a variable forward speed and reverse transmission, power means for operating the transmission comprising a power actuator operably connected to the transmission, a combined vacuum and spring operated means for insuring either (1) a low or reverse operation of the transmission or (2) a second or high gear operation of the transmission by the actuator, the operation of said means being a function of the condition of the vehicle, that is whether static or kinetic, and means controlling with said second mentioned means for controlling the operation of the actuator to select any one of the gear ratios of the transmission.

15 25. A power operated accessory unit for operating the shift lever of an automotive vehicle comprising a double-acting vacuum operated actuator operably connected to the lever and pivotally mounted on the dash of the vehicle, valve means for controlling the operation of said motor, said valve mechanism comprising a ported casing member and a reciprocable piston slidable within said casing, said casing and piston being constructed to provide two three-way valve members, and a foot-operated treadle member for operating said valve piston member.

20 26. Power means for operating the shift lever of the transmission of an automotive vehicle comprising a double-acting actuator operably connected to the lever, valve mechanism for controlling the operation of the actuator and its connected lever to simulate a conventional manual operation of the lever, said valve mechanism

comprising a double three-way valve for controlling reciprocation of the power element of the actuator to move the lever to any one of its operative positions, said valve mechanism further comprising a solenoid operated three-way valve 5 operable to control the operation of the actuator to neutralize the position of the shift lever, if in any one of its operative positions, and, if neutralized from either its high or second gear position, to then move the lever laterally to a position to insure either a low or a reverse gear operation of the shift lever.

10 27. Power means for operating the shift lever of the transmission of an automotive vehicle comprising a double-acting actuator operably connected to the lever, valve mechanism for controlling the operation of the actuator and its connected lever to simulate a conventional manual operation of the lever, said valve mechanism comprising a manually operable double three-way 15 valve selectively operable to control the reciprocation of the power element of the actuator to move the lever to any one of its operative positions, said valve mechanism further comprising a solenoid operated three-way valve operable by 20 a vehicular operated speed responsive means to control the operation of the actuator, when the vehicle is static or substantially so, to neutralize the position of the shift lever, if in any one of its operative positions, and, if neutralized from either its high gear or second gear positions, to then move the lever laterally to a position to insure either a low or a reverse gear operation of the lever.

25 28. In an automotive vehicle provided with a driver's compartment and a transmission shift lever within said compartment, power means for operating said lever to simulate a conventional operation thereof, said power means comprising a power actuator pivotally mounted to the vehicle body defining a portion of said compartment and adapted for angular bodily movement in a horizontal plane, said power actuator including a power member operatively connected to the shift lever, and further including a vacuum operated power means for imparting angular movement to itself to move the shift lever through the gate of the transmission.

CERTIFICATE OF CORRECTION.

Patent No. 2,175,662.

October 31, 1939.

VICTOR W. KLIESRATH, ET AL.

It is hereby certified that error appears in the printed specification of the above numbered patent requiring correction as follows: Page 1, second column, line 5, for the word "conduit" read --conduits--; page 2, first column, line 27-28, for "operateate" read --operate--; line 52, after "of" insert --a--; same page, second column, line 54, for "7" read --17--; page 6, first column, line 55, for the word "propelled" read --propeller--; page 7, first column, line 54, for "later" read --latter--; page 9, second column, line 52, claim 11, for the word "shaft" read --shift--; and that the said Letters Patent should be read with this correction therein that the same may conform to the record of the case in the Patent Office.

Signed and sealed this 21st day of January, A. D. 1941.

(Seal)

Henry Van Arsdale,
Acting Commissioner of Patents.
